UNITED STATES PATENT OFFICE.

MARSHALL W. GLEASON AND CLARENCE G. MILLER, OF BROOKLYN, NEW YORK,
ASSIGNORS TO GLEASON-TIEBOUT GLASS COMPANY, OF BROOKLYN, NEW YORK, A
CORPORATION OF NEW YORK.

GLASS LEER.

Application filed November 24, 1924. Serial No. 752,014.

To all whom it may concern:

Be it known that we, MARSHALL W. GLEASON and CLARENCE G. MILLER, of the borough of Brooklyn, county of Kings, city 5 and State of New York, have invented certain new and useful Improvements in Glass Leers, of which the following is a specification.

Our invention relates to glass leers, more 10 particularly to an attachment therefor, the object being to produce such an attachment which can be removably placed and connected with an existing leer for the purpose of "firing in" colors on vitreous wares.

Our invention is shown in the accompanying drawings in which Figure 1 is a longitudinal side elevation, partly broken away 15 to show interior details: Figure 2 is a front or end view, the upper door being closed and the lower door being shown open, and Figure 3 shows details of pans and connecting rod, in perspective. Similar reference characters refer to similar parts in the several views.

The body forms a chamber 1, rectangular in cross section, and of a size suited for the opening of the leer proper, L, and consists 20 preferably of galvanized sheet iron, strengthened and braced by a framework of iron, 2, and supported by several pairs of legs, 3, with rollers 3'.

At the intake end doors, 4, 5, are provided: angles, 6, 7 are fastened to the bottom of the chamber to act as guides or rails 25 for the transitory pans, 8: these pans are connected with each other by links, 9, pivotally mounted near the end of one pan and engaging a notch, 10, in the adjoining pan, as shown. Any other preferred way of 30 joining the pans may be used, this being a minor detail.

A curtain, 11, of strips of asbestos, suspended from the roof of the chamber at the proper point conserves the heat coming 35 from the leer L: one or more ventilators, 12, may be used for regulating the temperature within the chamber.

A removable rest, 13, for the loading of 40 the pans with wares to be fired is connected to the body by hooks, 13' which slips over a rod, 14, fastened to the body, 1.

A rod, 15, flattened and bent at right angles at one end, 15', and bifurcated at the

other end 15" is adapted to draw the pans through the chamber and into the leer L by 45 means of the mechanism, M, in the leer. A simple means is shown for drawing the pans into the leer; any other well known method may be employed to suit the particular requirements as this detail is a minor one. 50

Such being the construction, the operation is as follows:—When it is desired to "fire" 55 a group of wares which have been previously decorated, the attachment is rolled over and connected with the mouth of any leer L, which has its heating means, H, at or near the front and is also provided with the usual rotary mechanism, M, to advance the pans through the leer, as is usual in glass annealing leers. Any opening or space between the mouth of the leer and the body of our improved attachment can be filled in or stopped off with asbestos so that no heat will escape except through the chamber of the attachment. 75

The doors, 4, 5, are opened and secured in that position in any preferred way, and the pan rest, 13, placed in position, as shown. Wares to be "fired" are placed on the pan, and when ready, the rod, 15, is passed through the chamber and connected with the links, 9, on both sides of the pan; the other end of the rod being flattened and bent at right angles engages the mechanism, M, of the leer by which the pan is slowly 80 drawn toward the leer proper. Another pan is placed on the rest and filled with wares, the links, 9, engage the notches, 10, and the pan will be drawn into the chamber by the pan just previously loaded, and the operation 85 is repeated indefinitely to conclusion, when the pan rest, 13, is removed and the doors, 4, 5, are closed.

As the open or loading end of the chamber is the coolest part of it, the ware entering there is gradually warmed as it advances toward the leer, the curtain, 11, and ventilators, 12, being used to regulate the degrees of heat. As the pans move very slowly, by the time they reach the leer 90 proper the wares placed on them for "firing" will have been sufficiently preheated so that when they encounter the high heat of the leer proper the colors will fuse and be fixed without danger of cracking or breaking. 100 The pans and wares continues on

through the leer until they reach the far end which is cool enough so that ware can be removed from the pans, as usual.

Such being our invention what we claim and desire to secure by Letters-Patent is:

1. A removable attachment to leers, composed of a body forming a chamber, one end of which is adapted to connect with the mouth of a leer, means of closing the free 10 end of said chamber and of interlocking pans adapted for transitory passage through said chamber.

2. A removable attachment for leers consisting of a body forming a chamber adapted for connecting with the mouth of a leer, of parallel rails at the bottom of said chamber, a series of interlocking pans to traverse said rails, of means for moving said pans in a direction toward said leer and of means 20 for closing the free end of said chamber.

3. An attachment for leers consisting of a body having elongated chamber, open at one end and provided with doors at the other end, means for regulating the temperature

within said chamber, of parallel rails fastened to the floor of said chamber, and pans adapted for transitory passage through said chamber, and of means for drawing said pans through and away from said chamber to and through a leer to which said attachment has been connected.

4. A removable attachment to glass leers composed of a body forming an elongated chamber, one end of which is adapted to connect with the mouth of a leer, of parallel 35 rails on the floor of said chamber, of interlocking pans traversing said rails and of means for moving said pans into and through said chamber.

In testimony whereof we have hereunto 40 set our hands in the presence of two witnesses.

MARSHALL W. GLEASON.
CLARENCE G. MILLER.

Witnesses for both:

CORNELIUS H. TIEBOUT, Jr.,
HARRY T. TAYLOR.
